CABINET

John B. Suomala, Haddonfield, N. J., assignor to
 Radio Corporation of America, a corporation of
 Delaware

Application April 30, 1941, Serial No. 391,159

9 Claims. (Cl. 312—22)

This invention relates to cabinets, and more particularly to a cabinet for housing sound-reproducing apparatus.

Phonographs and combination phonographs and radio receivers are generally housed in cabinets provided with hinged lids for the purpose of affording easy access to the phonograph compartment in order to facilitate changing records and adjusting the parts of the phonograph above the motor board. Generally, it is desirable to place an ornamental article on the top of the cabinet such as a vase, picture, or the like, and every time one wishes to use a phonograph housed in a cabinet of this type, it becomes necessary to remove the articles from the lid before it can be raised in order to reach the phonograph parts. This not only constitutes a nuisance, but often acts as a deterrent to the use of the phonograph.

The primary object of my present invention is to provide an improved cabinet wherein the aforementioned difficulty is eliminated.

More particularly, it is an object of my present invention to provide an improved cabinet for phonographs or the like wherein the lid has a fixed relation to the walls of the cabinet, yet wherein ready access is afforded to the phonograph housed therein.

Another object of my present invention is to provide an improved phonograph cabinet from which the phonograph may be removed with great facility for the manipulation or adjustment of the phonograph parts.

Still another object of my present invention is to provide an improved phonograph cabinet as aforesaid wherein the phonograph compartment is of minimum size.

A further object of my present invention is to provide an improved phonograph cabinet which may be made advantageously of low height while affording convenient access to the phonograph.

It is also an object of my present invention to provide an improved phonograph cabinet as aforesaid which is simple in construction, occupies a minimum of space, and is highly efficient in use.

In accordance with this invention, I provide a cabinet having front, back and side walls to which is secured a top in fixed relation to the walls. The front wall is provided with an opening and has a cover hinged thereto in a position such that the cover may be moved into closed relation with said opening, or it may be lowered into an open position with respect to said opening, the cover extending downwardly away from the front wall at a slight inclination in an outward direction

when in the latter position. Secured to the side walls within the cabinet are a pair of supporting members which are inclined at substantially the same angle as the cover when the latter is in open position, the cover thus, in effect, then constituting an extension of the supporting members. A suitable platform which is adapted to carry sound-reproducing apparatus, such as a phonograph, is movably mounted on the supporting members and normally occupies a concealed position within the cabinet when the cover is closed, the platform being latched in this position by suitable latching mechanism. The cover carries a trip device which actuates the aforementioned latching mechanism as the cover is lowered to its open position to thereby release the platform so that the latter can move out, under the influence of gravity, to a position over the cover, thereby exposing the phonograph sufficiently to afford ready access thereto. Preferably, the supporting members and the cover are provided with cooperating rails or the like which guide the movement of the phonograph-supporting platform. Also, if desired, one or more resilient members, such as coil springs, rubber blocks, or the like, may be provided either on the back wall of the cabinet or on the rear edge of the platform to be compressed between the rear edge of the platform and the back wall of the cabinet when the platform is in fully inserted position within the cabinet. The energy stored in the resilient members may then be availed of to impart a starting impulse to the platform when the latch mechanism has been unlatched to release the platform, thereby insuring movement of the platform out of the cabinet.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawings, in which

Figure 1 is a sectional view through a cabinet constructed according to this invention and showing, in full lines, an automatic phonograph wholly within the cabinet, and in dot-and-dash lines, the phonograph moved out from the cabinet and over the lowered cover,

Figure 2 is a sectional view taken on the line II—II of Figure 1,

Figure 3 is a fragmentary sectional view taken on the line III—III of Figure 2, but showing, in

full lines, the cover closed and the phonograph-supporting platform in its rest position, and in dot-and-dash lines, the cover almost in its lowered position and the latch mechanism in position just about to release the platform for movement out of the cabinet,

Figure 4 is a view similar to Figure 3, taken on the same section line, but corresponding to Figure 2, wherein the record-supporting platform is shown reinserted into the cabinet prior to closing the cover,

Figure 5 is a fragmentary sectional detail view taken on the line V—V of Figure 2, and

Figure 6 is a plan view of the trip device carried by the cover.

Referring more particularly to the drawings, wherein similar reference characters designate corresponding parts throughout, there is shown a cabinet comprising a front wall 1, a back wall 5, side walls 7 and 9, and a top 11 secured to the walls 5, 7 and 9 in fixed relation thereto, so that the top or lid 11 cannot be moved relative to the walls, the front wall 1 terminating short of the top 11 so as to provide an opening 3 which affords communication between the exterior and the interior of the cabinet. Pivotedly mounted on the wall 1, as by a hinge 13, is a panel 15 constituting a cover for the opening 3, the cover 15 being movable from a closed position over the opening 3, as shown in solid lines in Figure 3, to an open position relative to the opening 3 wherein the cover 15 is inclined downwardly about 2 or 3 degrees with respect to the cabinet wall 1 in a forward direction, as clearly shown in Figures 1 and 4, the cover 15 being held in the latter position by a pair of fall supports 16 or the like.

Secured to the side walls 7 and 9 of the cabinet are a pair of supporting blocks 17 and 19, each inclined downwardly from the back wall 5 to the front wall 1 at substantially the same angle as the cover 15 when the latter is in its fully opened position, as shown in Figure 1. Thus, the cover 15 constitutes, in effect, an extension of the supporting members 17 and 19 when the cover is in its open position. The supporting members 17 and 19 are provided with upwardly extending side rails 17a and 19a, respectively, with which are aligned a pair of oppositely disposed rails 21 and 23 on the cover 15, the rails 21 and 23 thus constituting extensions of the rails 17a and 19a and being provided for a purpose shortly to be set forth.

Rotatably mounted on the supporting members 17 and 19 and guided in their movement therewith by the rails 17a and 19a are a plurality of rollers 25 rotatably carried by a pair of oppositely disposed brackets 27 and 29 secured to the underside of a platform 31 upon which is mounted a suitable phonograph or the like 33. The phonograph 33 may be of any suitable or well-known construction, and that illustrated herein is of the type adapted to automatically play a number of records in succession and is preferably of the type disclosed and claimed in the copending application of Benjamin R. Carson and Knut J. Magnusson, Serial No. 286,988, filed July 28, 1939, and assigned to Radio Corporation of America. Inasmuch as the details of this phonograph form no part of the present invention, a further description thereof is not believed to be necessary.

In view of the fact that the platform 31 and its phonograph 33 are carried on the inclined supporting blocks 17, it will be obvious that the platform 31 will constantly tend to roll out of the cabinet to the dot-and-dash line position of

Figure 1. It is therefore necessary to provide means for retaining the platform 31 and the parts carried thereby within the cabinet. For this purpose, a bar 35 may be secured to the bottoms of the supporting members 17 and 19, as clearly shown in Figures 1, 3 and 4. The bar 35 carries a mounting block 37 on which is pivotally mounted a latching lever 39 formed with a latching toe 39a and a shoulder 39b between which is formed a depression 39c. The platform 31 may be provided with a front wall 31a to the lower edge of which is secured a latch plate 41 having an upstanding flange 41a adapted to be engaged by the latching toe 39a to releasably hold the platform 31 within the cabinet, the lower edge of the lever 39 resting on the upper end of a screw 42 threadedly received in the bar 35 and the block 37 and adjustable thereon to limit the overlap of, or extent of engagement between, the toe 39a and the flange 41a.

Secured to the cover 15 is a trip plate 43 which pivotally carries a trip lever 45, the trip lever 45 being constantly urged in a clockwise direction relative to the trip plate 43 by a coil spring 47, as viewed in Figures 3 and 4. In the closed position of the cover 15, the trip plate 43 and its trip lever 45 occupy the solid line position shown in Figure 3. As the cover 15 is lowered toward its fully opened position, the trip lever 45 engages the shoulder 39b of the latch lever 39 shortly before the cover 15 and the latch plate 43 are in approximately the dot-and-dash line position shown in the same figure. Counterclockwise rotation of the trip lever 45 relative to the trip plate 43 is limited by engagement of the shoulders 45a on the trip lever 45 with the trip plate 43. Consequently, as the upper edge of the trip lever 45 engages the shoulder 39b of the latch lever 39, the latter will be moved clockwise on its pivot, as viewed in Figures 3 and 4, until its toe 39a is freed from the flange 41a on the latch plate 41. The platform 31 is then rendered free to move along the supporting members 17 under the influence of gravity to a position over the cover 15, the rails 17a, 19a, 21 and 23 guiding the movement of the platform 31. The lever 39 meanwhile falls back onto the upper end of the screw 42, the trip lever 45 being received in the depression 39c. A pair of downwardly extending posts or the like 49 secured to the rear wall of the platform 31 cooperate with a pair of rubber bumpers or the like 51 carried by some fixed part of the cabinet, such as the supporting blocks 17 and 19, for limiting the outward movement of the platform 31 and the phonograph 33, the bumpers 51 serving also to absorb the shock of the moving platform as it comes to rest over the cover 15.

It will be obvious that, with the top 11 fixed to the walls of the cabinet, and therefore free to receive suitable articles of ornamentation which need not be disturbed, access to the phonograph 33 may not be had through the top of the cabinet. However, when the cover 15 is open and the phonograph 33 has moved to the dot-and-dash line position of Figure 1, access may be readily had to the phonograph for the purpose of changing records and manipulating the various parts thereof. After the records R have been loaded and the pickup device P has been deposited on a record to be played, the platform 31 and the parts carried thereby may be pushed back into the cabinet to the solid line position of Figure 1, this being the rest position of the platform 31 and its phonograph 33.

When the platform is returned to its rest posi-

tion, the upstanding flange 41a on the latch plate 41 engages the inclined edge 39d of the toe 39a to cam the latching lever 39 in a clockwise direction about its pivot until the flange 41a has passed the toe 39a, after which the latching lever 39 drops back against the screw 42 to bring its toe 39a into latching engagement with the flange 41a again. Thereafter, as the cover 15 is moved to its closed position, the trip lever 45 engages the shoulder 39b and is momentarily arrested. As the cover continues movement toward its closed position, the trip plate 43 moves with it in a clockwise direction, as shown in Figures 3 and 4, and the spring 47 yields until the upper edge of the trip lever 45 has passed beyond the shoulder 39b, after which the trip lever 45 is reset by the spring 47 to the position shown in solid lines in Figure 3 so that the trip lever 45 will again be in readiness to properly engage the shoulder 39b when the cover 15 is next opened to thereby again release the platform 31 as above described.

Inasmuch as the inclination of the supporting members 17 and 19 is only slight with respect to a horizontal plane, it is helpful to impart to the platform a starting impulse when the latching lever 39 has been moved out of latching relation with the latch plate 41. For this purpose, there may be provided either on the back wall of the platform 31 or on the back wall 5 of the cabinet one or more compressible members such as coil springs or rubber blocks 53. As the platform 31 is returned to its rest position, the blocks, springs, or the like 53 are compressed between the back wall of the platform 31 and the back wall 5 of the cabinet to store sufficient energy therein to impart an initial or starting impulse to the platform when it is freed to move out of the cabinet.

From the foregoing description, it will be apparent to those skilled in the art that I have provided an improved cabinet for sound-reproducing apparatus which, while affording ready access to this apparatus, nevertheless retains the advantages of a cabinet with a fixed top. Moreover, it will be obvious that only a minimum of space is necessary for the sound-reproducing apparatus in a cabinet constructed according to this invention.

Although I have shown and described but one embodiment of my invention, it will be apparent to those skilled in the art that many other modifications thereof, as well as changes in the one herein described, are possible. I therefore desire that my invention shall not be limited except insofar as is made necessary by the prior art and by the spirit of the appended claims.

I claim as my invention:

1. A cabinet including a plurality of walls arranged to provide an opening which affords communication between the exterior and the interior of the cabinet, a cover pivotally mounted on one of said walls and adapted to close said opening, said cover being movable from closed relation with said opening to an open position inclined downwardly away from said last-named wall, supporting means in said cabinet inclined therein similarly to and substantially in extension of said cover when said cover is in said open position, a platform adapted to receive an instrument movably mounted on said supporting means and adapted, when said cover is moved into said open position, to move out from said cabinet onto said cover under the influence of gravity, means normally latching said platform within said cabinet against movement out of said cabinet, and means cooperatively associated with said cover for actuating said latch means as said

cover is moved toward said inclined position to free said platform for movement out of said cabinet onto said cover.

2. A cabinet including a plurality of walls arranged to provide an opening which affords communication between the exterior and the interior of the cabinet, a cover pivotally mounted on one of said walls and adapted to close said opening, said cover being movable from closed relation with said opening to an open position inclined downwardly away from said last-named wall, supporting means in said cabinet inclined therein similarly to and substantially in extension of said cover when said cover is in said open position, a platform adapted to receive an instrument movably mounted on said supporting means and adapted, when said cover is moved into said open position, to move out from said cabinet onto said cover under the influence of gravity, means normally latching said platform within said cabinet against movement out of said cabinet, means cooperatively associated with said cover for actuating said latch means as said cover is moved toward said inclined position to free said platform for movement out of said cabinet onto said cover, and means cooperatively associated with said platform for imparting thereto a starting impulse after said latch means has been actuated to free said platform.

3. A cabinet including a plurality of walls arranged to provide an opening which affords communication between the exterior and the interior of the cabinet, a cover pivotally mounted on one of said walls and adapted to close said opening, said cover being movable from closed relation with said opening to an open position inclined downwardly away from said last-named wall, supporting means in said cabinet inclined therein similarly to and substantially in extension of said cover when said cover is in said open position, a platform adapted to receive an instrument movably mounted on said supporting means and adapted, when said cover is moved into said open position, to move out from said cabinet onto said cover under the influence of gravity, means normally latching said platform within said cabinet against movement out of said cabinet, means cooperatively associated with said cover for actuating said latch means as said cover is moved toward said inclined position to free said platform for movement out of said cabinet onto said cover, and means cooperatively associated with one wall of said cabinet and with said platform for imparting thereto a starting impulse after said latch means has been actuated to free said platform.

4. A cabinet including a plurality of walls arranged to provide an opening which affords communication between the exterior and the interior of the cabinet, a cover pivotally mounted on one of said walls and adapted to close said opening, said cover being movable from closed relation with said opening to an open position inclined downwardly away from said last-named wall, supporting means in said cabinet inclined therein similarly to and lying substantially in the same plane as said cover when said cover is in said open position, a first pair of rails carried by said supporting means, a second pair of rails carried by said cover, said second pair of rails being aligned with and constituting an extension of said first pair of rails when said cover is in said open position, a platform in said cabinet adapted to receive an instrument, said platform being movably mounted on said supporting means in

association with said first pair of rails, means normally latching said platform in rest position within said cabinet, and means cooperatively associated with said cover for releasing said latching means from latching relation with said platform as said cover is moved to its open position whereby to free said platform to move out onto said cover and into association with said second pair of rails under the influence of gravity to thereby expose said instrument.

5. The invention set forth in claim 4 characterized in that the walls of said cabinet comprise front, back and side walls, characterized further in that said opening is provided by said front wall, and characterized still further by the addition of a top fixed to said walls.

6. The invention set forth in claim 4 characterized by the addition of a plurality of rollers on said platform, having rolling engagement with said supporting means adjacent said rails.

7. The invention set forth in claim 4 characterized in that said cabinet includes a back wall, and characterized further by the addition of compressible means cooperatively associated with said platform and said back wall and adapted to be compressed to store energy therein upon insertion of said platform into said cabinet to the rest position thereof whereby, upon subsequent release of said latching means, said compressible means is adapted to impart a starting impulse to said platform in response to the energy stored therein.

8. The invention set forth in claim 4 characterized in that said latching means comprises a latch plate carried by said platform, and a latch lever pivotally carried by said cabinet, said latch

lever including a toe adapted to engage said latch plate to releasably hold said platform in said rest position and also including a shoulder, and characterized further in that said releasing means comprises a trip plate secured to said cover and a trip lever pivotally carried by said trip plate, said trip lever being arranged to engage said shoulder to move said latch lever out of latching relation with said latch plate upon movement of said cover toward its open position.

9. The invention set forth in claim 4 characterized in that said latching means comprises a latch plate carried by said platform and having a flange thereon, and a latch lever pivotally carried by said cabinet, said latch lever including a toe adapted to engage said flange to releasably hold said platform in said rest position and also including a shoulder spaced from said toe, said latch lever being formed with a depression between said toe and said shoulder, and characterized further in that said releasing means comprises a trip plate secured to said cover and a trip lever pivotally carried by said trip plate, said trip lever being arranged to engage said shoulder to move said latch lever out of latching relation with said latch plate upon movement of said cover toward its open position whereby to free said platform for movement out of said cabinet, said trip lever extending into said depression after release of said platform, and characterized still further in that said flange and said toe are so constructed and arranged that, upon subsequent insertion of said platform into said cabinet, said flange engages and slips past said toe whereupon said toe again latches said platform in its rest position.

JOHN B. SUOMALA.
